SWIMMING POOL WATER PURIFIER TANK OR SIMILAR ARTICLE

Walter J. Polens, 398 Broadway Drive,
Pittsburgh, Pa. 15236

Filed Mar. 27, 1974, Ser. No. 455,440

Term of patent 14 years

Int. Cl. D23—01

U.S. Cl. D23—3

FIG. 1

FIG. 2

FIG. 3

FIG. 1 is a front elevational view of a swimming pool water purifier tank or similar article showing my new design;

FIG. 2 is a side elevational view thereof; and

FIG. 3 is a top plan view thereof.

I claim:

The ornamental design for a swimming pool water purifier tank or similar article, substantially as shown.
